TOY SHOWER

Salvatore P. Cucuzza, 3803 Dorchester Road, Philadelphia, Pa., and Robert S. Anzalone, 12 Glendale Road, Havertown, Pa.

Filed Aug. 12, 1963, Ser. No. 301,465
5 Claims. (Cl. 239—211)

This invention relates generally to toys, and is especially concerned with a unique toy-shower construction.

During hot summer weather, as is well known especially in large cities, it is conventional to open fire hydrants for cooling play in the water. This is very attractive to children and provides a source of healthy entertainment.

It is an object of the present invention to provide a unique toy-shower construction adapted to simulate in appearance and result the above-described fire-hydrant usage; and moreover, which is capable of private employment, say in one's back yard.

It is a further object of the present invention to provide a toy shower of the type described which is highly attractive in appearance, light in weight, and entirely safe for use even by small children.

Still another object of the present invention resides in the provision of a toy shower having the advantageous characteristics mentioned in the preceding paragraphs, which is extremely simple in construction, durable and reliable throughout a long useful life, and which can be economically manufactured for sale at a reasonable price.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

In the drawings:

FIGURE 1 is an elevational view showing a toy-shower construction of the present invention in operative condition of use;

FIGURE 2 is an elevational view taken at right angles to the view of FIGURE 1;

FIGURE 3 is a partial sectional elevational view taken generally along the line 3—3 of FIGURE 2; and

FIGURE 4 is a horizontal sectional view taken generally along the line 4—4 of FIGURE 2.

Referring now more particularly to the drawings, the toy shower of the instant invention is there generally designated 10, and includes a pedestal 11 adapted to seat on a ground surface 12.

The pedestal 11 may be advantageously integrally fabricated of plastic, say by blow-molding or other suitable procedure, and configured and decorated to accurately simulate the external appearance of a conventional fire hydrant.

More particularly, the pedestal 11 may include an upright hollow column 14 having at its lower end a generally peripheral flange 15 adapted to seat on the ground 12. The upper end of the column 14 may be provided with a domed closure 16 bounded by a peripheral bead or flange 17 and carrying an upstanding lug 18, all in simulation of a fire hydrant.

Depending from the underside of lower-end flange 15, circumferentially about the column 14, may be a plurality of stakes or pins 19. The stakes or pins 19 may be integral with the flange 15, or separate and inserted therethrough for impaling in the ground 12 to firmly hold the column 11 in its upstanding condition against reactive water forces and other incidents of use.

2

A generally horizontal conduit or tube 20, of considerably smaller diameter than the column 14, extends, transversely or diametrically through the column at a location spaced medially between the lower and upper ends thereof.

5 The tube 20 may also be fabricated of plastic, either integrally with or separate from the column 14 and suitably fixed to the latter. Provided on one end of the tube 20, extending through the wall of column 14 and projecting laterally outward therefrom is a tubular extension or connection nipple 21. The connection nipple 21 may be suitably threaded, as at 22 for threaded engagement with a conventional garden hose or other water-supply conduit, as will appear presently. Of course, the nipple 21 may be internally threaded, if desired, or suitable provision 10 may be made for connection by means other than threads.

Extending from the other end of conduit or tube 20, externally of the column 14, on the side opposite to nipple 21, is an enlarged hollow body or spray head 23. The hollow body or spray head 23 has its interior in 15 fluid communication with the interior of tube 20, and is externally configured in simulation of a fire-hydrant closure or cap. The upper side of the spray head 23 is advantageously formed with one or more discharge openings, such as arcuate slot 24.

25 In use, the column 14 is set upright on the ground surface 12 and secured in position by impaling of the stakes 19 into the ground. A garden hose or other suitable water-supply conduit may be connected to the connection nipple 21 for delivering water to the tube 20.

20 The delivered water passes from the tube, to the spray head 23 and is there discharged in an upwardly directed 30 stream as a water shower.

From the foregoing, it is seen that the present invention provides a toy shower which fully accomplishes its intended objects and is well adapted to meet practical conditions of manufacture and use.

35 Although the present invention has been described in some detail by way of illustration and example for purposes of clarity of understanding, it is understood that certain changes and modifications may be made within the spirit of the invention and scope of the appended claims.

What is claimed is:

1. A toy shower comprising an upstanding hollow column externally configured to simulate a fire hydrant, a conduit-connection nipple projecting laterally from one region of said column, a spray head projecting laterally from an opposite region of said column and externally configured to simulate a fire-hydrant closure, and fluid-conduit means extending transversely through said column in fluid communication between said nipple and spray head, whereby a water supply connected to said nipple is adapted to be discharged from said spray head.

45 2. A toy shower according to claim 1, in combination with a flange on the lower end of said column, and stakes depending from said flange for impaling in the ground, to resist the reactive force of water being discharged from said spray head.

3. A toy shower according to claim 2, said fluid-conduit means comprising a tube extending in spaced relation across the interior of said column.

46 4. A toy shower according to claim 3, said spray head having an upwardly facing opening for discharging an upwardly directed stream.

5. A toy shower comprising a generally cylindrical upstanding column, ground-impaling means on one end of said column for retaining the latter in upstanding condition, a conduit of smaller diameter than said column extending diametrically therethrough intermediate the ends of said column, a hose nipple projecting from one end of said conduit externally of said column, and a spray head projecting from the other end of said conduit ex-

3

ternally of said column, said spray head comprising a hollow body having a discharge opening in its upper side.
